UNITED STATES PATENT OFFICE.

ELMER J. LEE, OF BANGOR, PENNSYLVANIA.

DISTRIBUTOR.

Application filed November 11, 1922. Serial No. 600,416.

To all whom it may concern:

Be it known that I, ELMER J. LEE, a citizen of the United States, and a resident of Bangor, in the county of Northampton and State of Pennsylvania, have invented certain new and useful Improvements in Distributors, of which the following is a specification.

My present invention relates generally to 10 distributors, and more particularly to a distributor including a shell or casing disposed around the timer shaft and provided with an inner annular shoulder forming a trackway and constituted in part by the 15 fiber or other insulating material within the casing or shell and in part by metal contact plates which the fiber or other material insulate from one another.

In the ordinary construction the trackway within the shell or casing is traversed 20 by a roller carried by a spring controlled arm which is pivotally connected to a supporting member in turn connected to the timer shaft, so that in its rolling action upon 25 the trackway, the roller trails the supporting arm and is on account of this position and support particularly susceptible to vibratory movement toward and away from the surface of the trackway so that the latter 30 frequently becomes quickly worn in ridges and when so ridged obviously precludes smooth rolling contact of the parts.

It is the object of my present invention to 35 provide a rotor capable of quick easy attachment to a timer shaft and of operation within the usual casing or shell with a uniformly continuing smooth rolling contact and which for this purpose avoids the jointed construction of rotor normally employed 40 and substitutes a roller which is yieldable with respect to its supporting means in a straight line radially with respect to the timer shaft and through the center of its support so that there is a direct instead of 45 an indirect pressure of the roller upon the trackway of the shell which avoids the susceptibility to vibrations to which the ordinary structure is subject.

A further object is the provision of a simple, cheap and durable rotor which may be readily substituted for the ordinary jointed

rotor within the usual distributor casing or shell.

In the accompanying drawing which illustrates my present invention and forms a part 55 of this specification,

Figure 1 is a section taken transversely through a distributor shell, showing the practical application of my improved rotor.

Figure 2 is a detail sectional view taken 60 through my improved rotor in a plane parallel to its plane of movement,

Figure 3 is a sectional view taken at right angles to Figure 2, and

Figure 4 is a detail perspective view of the 65 several parts of my improved rotor in detached relation.

Referring now to these figures I have shown in Figure 1 a conventional distributor shell generally indicated at 10 and presenting an inner annular shoulder 11 forming a trackway upon which the contact roller travels in operation, said shoulder or trackway being constituted in part by the fibrous or other insulating material 12 within the shell and in part by the flat metal distributing contacts 13 which the material 12 insulate from one another.

The shell 10 is indicated in its usual position around the timer shaft 14, upon which 80 it is usual to support the rotor of the distributor, carrying the contact roller, by means of a confining nut 15.

In the present instance the contact roller 16 is positioned in engagement with the 85 trackway or shoulder 11 in a radial line with respect to the timer shaft 14 which passes through the center of the support of the roller connected to the shaft, and the roller 16 is for this purpose mounted within a rectangular holder 17 having an outer convexly curved edge provided with a surrounding flange 18, the sides of the holder having opposed apertures 19 to receive a roller bearing pin 20 which passes also through the 90 axial opening 21 of the roller.

The holder 17 of the roller has a sliding fit within the outer portion of the roller support or cage generally indicated at 22, also having convexly curved outer edges 23, one 100 of which may be provided with an extending tongue 24 adapted to be bent inwardly

as indicated particularly in Figure 3 in order to overlap one side flange of the holder 17 and thus movably confine the holder within the cage and prevent its accidental displacement.

The cage or support 22 is generally rectangular and may be formed of a single piece of material bent angularly to constitute its sides and ends, one of these bent portions having an integral extension at the inner end of the cage, bent to form flat side shoulders 25 and a curved shaft embracing portion 26 between said side shoulders, this extension being preferably provided with a terminal tongue 27 adapted to be seated in conformable recesses at one side of the cage or support and flush with the latter. The shaft embracing portion 26 has a slot 28 to receive the usual pin 29 which when in place extends within a recess in the timer shaft 14, and which is held from displacement by a cap 30. This cap 30 when in place embraces one end of the shaft embracing portion 26 of the support or cage, and in so doing also covers the pin 29, the cap having side wings 31 adapted to engage opposite sides of the support or cage 22 so that when in turn engaged by the confining nut 15 upon the timer shaft projecting through an opening 32 of the cap, the latter will be immovably held.

The inner edges of the support or cage 22 at opposite ends of the shaft embracing portion 26 have inturned lugs 33 which bear against the timer shaft 14 as shown most clearly in Figure 3, and the shoulders 25 formed by the inner extension of this cage at opposite sides of the shaft embracing portion 26, serve as supports or abutments for the inner end of a coil spring 34 whose shape is preferably made to conform to the rectangular shape of the cage and the roller holder 17 and whose outer portion is adapted to surround the said roller holder 17 and engage the flange 18 of the latter, thus placing the roller holder and consequently the roller carried thereby under tension sufficient to hold the roller firmly and evenly in engagement with its trackway in a radial line from the timer shaft which passes through the center of the cage and the holder 17.

It is obvious from an inspection of the

parts that the objects of the invention first above stated as well as the structure of the several parts utilized, may be carried out in an extremely simple inexpensive manner, the support or cage 22, cap 30 and roller holder 17 being each capable of formation from a single piece of material, either cast or of sheet form bent to the shape described.

My invention provides a lasting efficient rotor which may be readily substituted for the usual rotor within the usual casing or shell, one which is inexpensive, and in particular one which avoids the known disadvantages of the present rotor.

I claim:

1. A rotor for timer shafts consisting of a rectangular support having its sides and ends formed by the bent portions of a single piece of material and open at its base, the meeting ends of said section of material at one side of the support being recessed and the other side of the support having an integral extension curved across the top of the support and forming with the upper edges of the ends of the support a shaft bearing, said extension having at its free end an angular tongue projecting into the recessed portion of the first mentioned side of the support, a contact roller, a rectangular flanged holder in which the contact roller is journaled and which is movable into the support through the lower open end of the latter, and a spring within the support engaging said roller holding to tension the latter and the roller.

2. A rotor for timer shafts including a rectangular support formed by the bent portions of a single piece of metal and open at its lower portion, one side of the support having an integral extension projecting across the top of the support and forming parallel side shoulders and a curved member between said side shoulders cooperating with the upper edges of the ends of the support to form a shaft bearing, a contact roller, a holder in which the roller is journaled, movable into the lower open portion of the support, and a spring within the support bearing against the said shoulders and engaging the said roller holder to tension the latter and the contact roller in practice.

ELMER J. LEE.
